Primary Examiner — Ian Simmons*Assistant Examiner* — Dana L Meyrow(74) Attorney, Agent, or Firm — Cynthia R. Miller(57) CLAIM

The ornamental design for a cosmetic container, substantially as shown and described.

DESCRIPTION

FIG. 1 is a top, front perspective view of our new design for a cosmetic container;

FIG. 2 is a top plan view of the cosmetic container shown in FIG. 1;

FIG. 3 is a front elevational view of the cosmetic container shown in FIG. 1; the rear and side elevational views being identical thereto; and,

FIG. 4 is a bottom plan view of the cosmetic container shown in FIG. 1.
